POWDER MEASURE STAND

Donald R. Tucker, Oroville, Calif., assignor to RCBS Inc.,
Oroville, Calif., a corporation of California

Filed Nov. 7, 1967, Ser. No. 9,367

Term of patent 14 years

U.S. Cl. D52—2
Int. Cl. D10—99

FIG. 1 is a perspective view of the powder measure stand illustrating my design with the powder measure depicted in phantom lines for illustrative purposes only.

FIG. 2 is a left side elevational view.

FIG. 3 is a rear view.

FIG. 4 is a top plan view.

The essential features of the design reside in the full line portions thereof.

I claim:

The ornamental design for a powder measure stand, as shown and described.
